UNITED STATES PATENT OFFICE.

MORRIS BARROW, OF NEW YORK, N. Y.

DRESS-SHIELD POCKET.

1,059,811.

Specification of Letters Patent.

Patented Apr. 22, 1913.

Application filed August 31, 1912. Serial No. 718,046.

To all whom it may concern:

Be it known that I, MORRIS BARROW, a subject of the Czar of Russia, and a resident of the city of New York, borough of 5 Manhattan, in the county and State of New York, have invented a new and Improved Dress-Shield Pocket, of which the following is a full, clear, and exact description.

The object of the invention is to provide 10 a new and improved dress shield pocket, more especially designed for use on washable garments, such as corset covers and the like, and arranged to permit the convenient inserting of a dress shield and retaining it 15 correctly in place therein, and to allow of removing the dress shield from the pocket immediately prior to washing the garment thus preventing injury to the dress shield while the garment is being washed. For 20 the purpose mentioned use is made of a dress shield pocket at each sleeve and formed in two parts, of which one part is attached to the sleeve at the under portion thereof and the other is secured to the in- 25 side of the body of the garment, the mouths of the two pocket parts being both open along the bottom scye, and a closing flap integral on the sleeve part of the pocket and adapted to overlie the pocket part to close 30 both pocket parts at the same time.

A practical embodiment of the invention is represented in the accompanying drawings forming a part of this specification, in which similar characters of reference indicate corresponding parts in both of the views.

Figure 1 is a perspective view of a corset cover provided with dress shield pockets; and Fig. 2 is an enlarged sectional side elevation of the dress shield pocket as applied 40 at one of the sleeves and with a dress shield in position therein.

The dress shield pocket is formed by two pocket parts A and B, of which the pocket 45 part A is sewed to the inside of the body C of the garment, while the other pocket part B is sewed to the inside of the sleeve D at the under portion and sides thereof, both pocket parts A and B being approximately 50 of crescent shape and having their mouths at the scye E of the garment. The sleeve pocket part B is provided with an integral closing flap F adapted to overlie the body pocket part A and adapted to be fastened thereto 55 by a fastening device G, such as a button

and buttonhole, as plainly indicated in the drawings. It is understood that when the flap F is open a dress shield H of the usual construction can be readily placed into the correspondingly-shaped pocket parts, and after this is done the flap F is moved into closed position and fastened to the body pocket part A by the use of the fastening means G. Portions F' of the sides of the flap, are sewed or otherwise attached to the 60 corresponding portions of the sides of the body pocket part A, so that when the flap F is in closed position it tends to clamp the shield corners in place in the pocket parts thus preventing the shield from curling up. 70 When it is desired to wash the garment the fastening means G are unfastened to allow of swinging the flap F into open position thereby permitting the user to remove the dress shield H from the pocket. 75

It is understood that dress shields are usually faced with rubber or a similar material impervious to moisture, and hence such dress shields when permanently fastened to the garment are liable to be spoiled 80 while washing the garment. By the use of the pockets shown and described the dress shields of a garment can be readily removed prior to washing, and can be conveniently replaced in the pockets after the garment is 85 washed. It is also understood that by making the pocket parts A and B similar in shape to the dress shield, the latter is held properly in place in the pocket parts especially as they are closed by the flap F. 90

Having thus described my invention, I claim as new and desire to secure by Letters Patent:

1. A corset cover or like washable garment, having a body, sleeves, and dress shield pockets at each sleeve, each pocket being formed of two parts arranged at opposite sides of the bottom of the scye, and of which parts one overlies the sleeve material of the garment and the other overlies the body material of the garment, the parts being secured along their sides to the said sleeve and body materials, the mouths of the pockets being open along the bottom of the scye for the insertion of a dress shield, 95 a closing flap integral on the sleeve part of the pocket and adapted to overlie the other body pocket part to close both pocket mouths at the same time, and fastening means for fastening the closing flap to the 100 105 110

body pocket part approximately midway between the said attached side edge portions of the flap.

2. A corset cover or like washable garment, having a body, sleeves, and dress shield pockets at each sleeve, each pocket being formed of two parts arranged at opposite sides of the bottom of the scye, and of which parts one overlies the sleeve material of the garment and the other overlies the body material of the garment, the parts being secured along their sides to the said sleeve and body materials, the mouths of the pockets being open along the bottom of the scye for the insertion of a dress shield, a closing flap integral on the sleeve part of the pocket and adapted to overlie the other

body pocket part to close both pocket mouths at the same time, portions of the side edges of the said closing flap being attached to the corresponding side edges of the body pocket part, and fastening means for fastening the closing flap to the body pocket part approximately midway between the said attached side edge portions of the flap.

In testimony whereof I have signed my name to this specification in the presence of two subscribing witnesses.

MORRIS BARROW.
